Application October 26, 1933, Serial No. 695,281

6 Claims. (Cl. 230—97)

The invention relates to the front end of coal fired locomotives; its object being to provide for the practical destruction of the small cinders which are carried out of the fire-box under the influence of the strong draft employed, and which, because of their rather small size and because they are of high temperature, are ordinarily referred to as sparks, and to accomplish this result without materially affecting the minus pressure developed in the smoke-box by the passage therethrough of the column of exhaust steam. Such cinders, if permitted to escape from the stack while in a state of combustion or at high temperature, become the cause of serious fires along the track. When sufficiently reduced in size they very quickly cool to such an extent that they are no longer sources of trouble.

A more detailed statement of the objects of the invention, and a full explanation of its mode of operation, are given in the following description.

In the accompanying drawings:

Fig. 1 is a detail vertical central longitudinal section of the front end of the body of the locomotive;

Fig. 2 is a detail transverse vertical section on the line 2—2 of Fig. 1;

Fig. 3 is a detail section on the line 3—3 of Fig. 1;

Figs. 4 and 5 are views in perspective of elements of the spark arrester.

The front end portion of a locomotive is represented at 10. The forward flue sheet is shown at 11. The front ends of boiler tubes are indicated at 12, and are connected with a superheater, a portion of which is shown at 13. At 14, 15, are indicated steam pipes which lead to the engine cylinders, and at 16 the exhaust nozzle leading from such cylinders and discharging vertically through the smoke box 18 of the locomotive into the open end of the smoke stack 17, which projects through the top of the locomotive body.

A baffle plate 19 extends across the body 10 of the locomotive to the rear of the smoke stack, and defines the rear end of the smoke box 18. This baffle plate terminates some distance from the bottom of the body 10, as shown on a level with the upper end of the exhaust nozzle 16. A table plate 20 extends forwardly from the lower end of the baffle plate 19 over and beyond the nozzle 16, and is apertured in line with the throat thereof. This table reaches from side to side of the body 10 and is imperforate except as just explained. At the forward end of the plate 20 there is a for-

wardly and downwardly inclined deflector plate 21. The line of draft, therefore, from the flue sheet 11 to the smoke box 18 is under the table plate 20 and plate 21, the smoke being deflected downwardly as it enters the smoke box proper.

The spark arrester comprises an assembly of a plurality of flat circular plates, as 22, 23, 24, arranged in vertical order, secured together by means of through bolts 25 and spaced apart by pipe spacers 26, threaded upon these bolts. 10 These plates are as many in number as may be desired, and are centrally apertured. This assembly is interposed between the lower end of the smoke stack 17 and the table plate 20 by which it is supported, a centrally placed annular standard 27 being interposed between the plate 20 and the bottom plate of the spark arrester assembly. 15

The top and bottom plates of the arrester may be secured to the petticoat of the spark arrester and to the standard 27, and the latter to the 20 plate 20 by any suitable means. The apertures of the several plates of the spark arrester assembly are of increasing diameter from bottom to top, that of the lower plate being substantially of the diameter of the throat of the nozzle 16, 25 and that of the top plate being substantially of the diameter of the smoke stack 17.

Interposed between adjacent plates of the spark arrester assembly are a series of curved vanes, as 28, 29, extending inwardly from the margins 30 of the plates approximately to the central apertures thereof. As shown, these vanes are semi-circular in form. This particular form is not of vital importance, and they may be broadly described as open curves. Neither is the number of 35 vanes between each pair of plates of the essence of the invention. They are preferably uniformly spaced circumferentially, and are attached to at least one of the plates with which they are associated; as shown, they are cast integral with the 40 plate from which they rise. The vanes may all be curved in the same direction, as indicated in Fig. 1, or those of different sections may be oppositely curved, as shown in Figs. 4 and 5.

The spark arrester constructed as described 45 has the form of a circular body horizontally separated into a plurality of flue passages which are open to the smoke box throughout the entire circumference of the body, and are divided into a plurality of spiral flue passages leading to the 50 central apertures in the plates.

Smoke issuing from the usual openings in the flue sheet 11 passes forwardly under the plates 20, 21, and fills the entire chamber of the smoke box. The powerful draft induced by the column 55

of exhaust steam draws the smoke into the flue passages of the spark arrester from all radial directions. This suction will cause the smoke and the cinders carried by it to impinge forcibly upon the outer surfaces of the curved vanes. Due to this initial impact, to their frictional contact with the surfaces of the vanes, and to the abrasive action due to their violent contact with each other, the cinders are reduced to such small sizes that they quickly lose their high and dangerous temperatures and cease to be fire hazards.

The violent attrition action on the cinders thus secured is obtained without materially reducing the suction action in the fire-box due to the passage of exhaust steam through the smoke-box, as the inrush toward the steam column of the cinder-laden vapors within the smoke-box is not appreciably impeded by any baffles. The violent agitation of the solid particles and their reduction by impact and friction are secured, but the freedom of movement of the vapors is not materially impeded, and consequently the minus pressure developed in the smoke-box is as great as if the spark arrester were not present.

The invention is not limited in its scope to the specific form of construction disclosed. Changes in the particular form and number of curved vanes may be found desirable according to the quality or character of the fuel employed.

We claim as our invention:

1. A spark arrester for locomotives comprising a steam nozzle and a smoke stack in alignment and spaced apart, the stack being of greater diameter than the nozzle, a set of horizontal centrally apertured plates between the nozzle and stack, the apertures of the lower and upper plates being approximately of the same diameter as the nozzle and stack, respectively, and the apertures of the intervening plates being of gradually increasing diameter from the lowest to the highest, and a plurality of vertical curved vanes interposed between adjacent plates.

2. A spark arrester for locomotives, comprising a plurality of vertically spaced, horizontal, concentric, annular plates, curved vanes uniting adjacent plates and extending outwardly from the

margins of their apertures, the vanes being correspondingly curved and the spaces between their outer ends being unobstructed.

3. A spark arrester for locomotives, comprising a plurality of vertically spaced, horizontal, concentric, annular plates, vanes uniting adjacent plates and extending outwardly from the margins of their apertures, the vanes being correspondingly bowed and of approximately uniform length, the spaces between their outer ends being unobstructed. 10

4. A spark arrester for locomotives, comprising a plurality of vertically spaced horizontal, concentric, annular plates, a plurality of vanes joining adjacent plates, such vanes being substantially in the form of a segment of a circle, and extending inwardly from the margins of the plates, partially encircling the plate apertures, and terminating adjacent to the margins thereof. 15

5. A spark arrester for locomotives, comprising a plurality of vertically spaced horizontal, concentric, annular plates, a plurality of vanes joining adjacent plates, such vanes being substantially in the form of the segment of a circle, and extending inwardly from the margins of the plates, partially encircling the plate apertures, and terminating adjacent to the margins thereof, the spaces between the outer ends of the vanes being unobstructed. 25

6. A locomotive, having a smoke box, a smoke stack leading upwardly from the box, and an exhaust nozzle discharging upwardly into the box and in line with the stack, and a spark arrester comprising a pair of horizontal, concentric, annular plates attached respectively to the stack and nozzle, and a series of intermediate, relatively spaced, annular plates, intermediate of the first-named plates, a series of uniformly curved vanes located between each pair of plates and extending from the margin thereof approximately to 40 the margins of their apertures, and partially encircling such apertures, the spacings between the plates being otherwise unoccupied. 30 35
